US00D599798S

(12) **United States Design Patent**
Fitch et al.

(10) **Patent No.:** US D599,798 S
(45) **Date of Patent:** ** Sep. 8, 2009

(54) **HAND HELD COMPUTER DEVICE**

(75) Inventors: **Timothy R. Fitch**, Syracuse, NY (US);
Larry K. Hooks, Jr., Fort Mill, SC (US); **Brian V. Conti**, Matthews, NC (US)

(73) Assignee: **Hand Held Products, Inc.**, Skaneateles Falls, NY (US)

(**) Term: **14 Years**

(21) Appl. No.: **29/291,967**

(22) Filed: **Sep. 21, 2007**

Related U.S. Application Data

(62) Division of application No. 10/938,416, filed on Sep. 10, 2004, now Pat. No. 7,446,753.

(51) **LOC (9) Cl.** **14-02**

(52) **U.S. Cl.** **D14/426; D14/429**

(57) **CLAIM**

The ornamental design for a hand held computer device, as shown and described.

DESCRIPTION

FIG. 1 is a front perspective view of a hand held computer device according to the invention.

FIG. 2 is a first rear perspective view of a hand held computer device of FIG. 1.

FIG. 3 is a second rear perspective view of a hand held computer device of FIG. 1.

FIG. 4 is a first side view of a hand held computer device of FIG. 1.

FIG. 5 is a top view of a hand held computer device of FIG. 1.

FIG. 6 is a second side view of a hand held computer device of FIG. 1.

FIG. 7 is a bottom view of a hand held computer device of FIG. 1.

FIG. 8 is a front view of a hand held computer device of FIG. 1; and,

FIG. 9 is a rear view of a hand held computer device of FIG. 1.

The portions shown in broken line are not claimed.

1 Claim, 8 Drawing Sheets
